The ornamental design for a monocle case, as shown and described herein.

DESCRIPTION

FIG. 1 is a front perspective view of a monocle case in a closed position showing our new design;

FIG. 2 is a front perspective view of the monocle case opened;

FIG. 3 is a rear perspective view of the monocle case closed;

FIG. 4 is a rear perspective view of the monocle case opened;

FIG. 5 is a top view of the monocle case closed;

FIG. 6 is a top view of the monocle case opened;

FIG. 7 is a bottom view of the monocle case closed;

FIG. 8 is a bottom view of the monocle case opened;

FIG. 9 is a side view of the monocle case closed;

FIG. 10 is a side view of the monocle case opened;

FIG. 11 is a side view of the monocle case closed;

FIG. 12 is a side view of the monocle case opened;

FIG. 13 is a front view of the monocle case closed;

FIG. 14 is a front view of the monocle case opened;

FIG. 15 is a rear view of the monocle case closed; and,

FIG. 16 is a rear view of the monocle case opened.
